(57) CLAIM

The ornamental design for a golf club head face, as shown and described.

DESCRIPTION

This application claims benefit to U.S. Non-Provisional application Ser. No. 12/273,520 filed Nov. 18, 2008.

FIG. 1 is a front view of the golf club head face; and,
FIG. 2 is a perspective view of the golf club head face of FIG. 1.

The broken lines shown in the drawings are for descriptive purposes only.
